TELEVISION APPARATUS

Huston Harris, Corning, N. Y., assignor to Corning Glass Works, Corning, N. Y., a corporation of New York

Application July 18, 1936, Serial No. 91,403

2 Claims. (Cl. 250—141)

My invention relates to improvements in television apparatus and the like, and particularly to the improvement of the optical fidelity of such apparatus.

5 In the past it has been common practice to manufacture envelopes for cathode ray tubes, used in television receivers to display images translated from picture signals received, by blowing the envelopes to the desired contour. The 10 shape of the envelope usually is that of a funnel, closed at the large end to form a screen upon which the images are displayed; and having the electrical elements constituting an electron gun for developing a cathode ray and for 15 directing the same at the screen to produce images thereon, mounted in the stem. A similar practice has also been followed in the manufacture of the iconoscope tube which serves as a means for viewing scenes for television transmission and similar applications, and which is 20 composed of an envelope containing an electron gun focused on a photosensitive signal plate within the tube to develop picture signals in accordance with reflections received on the photosensitive signal plate of objects or scenes within 25 view of a window comprising a part of the tube envelope structure.

In the blowing of a glass body it is impossible 30 to obtain a perfect distribution and uniform thickness of glass in the wall, and while in ordinary vacuum tubes this may not be important, it is highly important in a cathode ray tube that the distribution, thickness and contour of the glass in that portion of the wall serving the 35 screen be uniform, as otherwise distortion of the image produced thereon will result. For similar reasons it is important that the thickness and contour of the window of an iconoscope tube be uniform, as otherwise the object reflections on 40 the signal plate will be distorted and fidelity of transmission and reproduction will be seriously impaired.

An object of the present invention is to transmit and reproduce pictures and views with fidelity.

45 Among its features my invention embodies a cathode ray tube envelope having a screen portion on which picture signals will be developed with perfect fidelity; also, an iconoscope tube envelope having a window therein through which light, reflected from objects or scenes within 50 view of the window, will pass without distortion.

Other features embody the production of a vacuum tube envelope by sealing or welding a pre-formed optical screen or window portion of

the envelope to a blown body portion thereof; the pre-formed body being produced in any well known manner, as by pressing, or by forming and subsequently grinding and polishing in accordance with the degree of perfection desired. 5

In the drawing:

Fig. 1 is a side view of a cathode ray tube having an envelope embodying this invention;

Fig. 2 is a side view, in section, of the blown and pressed parts of the envelope shown in Fig. 10 1 before they are sealed together;

Fig. 3 is a side view of an iconoscope tube having an envelope embodying this invention;

Fig. 4 is a view, similar to Fig. 2, of the parts 15 of an iconoscope tube envelope embodying this invention; and

Fig. 5 is an end view of the intermediate part 20 of the envelope shown in Fig. 4.

In the cathode ray tube the envelope is composed of a blown glass body portion 10, the large 25 end of which is carefully ground and sanded to free it of any metallic inclusions, and then welded or fused to a similarly prepared surface of a saucer-like pressed glass part 11 having a concavo-convex screen or rounded area 12 in which the mass of glass is of uniform thickness and curvature throughout. If desired, the screen 30 may be of plano-parallel configuration, but the concavo-convex configuration gives the exposed surface of the screen greater resistance to fracture, and also corrects distortion caused by the 35 changing curvature of the field with distance away from the cathode when a plano-parallel screen is used. An electron gun 13 of any known form is sealed in the neck of the envelope and 40 is directed toward the screen area 12 in the usual manner.

The iconoscope tube envelope comprises a main body in the form of a cylinder 16, the one 45 end of which is ground, sanded and then welded or fused to a similarly prepared surface of a saucer-like part of pressed glass or the like having a plano-parallel screen or window area 18 within its wall areas 19 and 20. The lower wall area 20 has a protuberance 21 partly ground off at the point indicated (Fig. 4) by the interrupted line 22 to form an apertured seat 22 to which a tubular part 23 of the envelope is welded at such an angle with respect to the axis of the cylinder 16 that an electron gun 24, sealed in the 50 remote end of tube 23, can scan the usual photosensitive mosaic surfaced signal plate 25 to develop picture signals in accordance with light reflected from objects or scenes within view of the window area 18.

It will be apparent from the foregoing that by the use of a combination of blown and pressed glass parts I am able to produce envelopes for cathode ray and iconoscope tubes or the like having screen or window areas of perfect optical fidelity.

What is claimed is:

1. An electron tube envelope made of glass which includes pressed optical and blown non-optical hollow sections arranged in juxtaposed relation and fused together at the adjoining edges, the optical section being so shaped that the major portion thereof is in a plane remotely

disposed with respect to the line of juncture of the respective sections.

2. A glass envelope which includes two separately fabricated hollow parts one of which is adapted to transmit light generated within the envelope, said parts being arranged in juxtaposed relation and fused together at their adjoining edges and the light transmitting part being so shaped that the larger portion thereof is in a plane remotely disposed with respect to the line of juncture of the respective parts.

HUSTON HARRIS.
